UNITED STATES PATENT OFFICE.

EDWIN C. WASHBURN, OF ENGLEWOOD, NEW JERSEY.

TRUCK BOLSTER.

Application filed June 24, 1921. Serial No. 480,156.

To all whom it may concern:

Be it known that I, EDWIN C. WASHBURN, a citizen of the United States, residing at Englewood, in the county of Bergen and State of New Jersey, have invented certain new and useful Improvements in Truck Bolsters; and I do hereby declare the following to be a full, clear, and exact description of the invention, such as will enable others skilled in the art to which it appertains to make and use the same.

This invention relates to a truck bolster for a railway car.

It is an object of this invention to construct such a bolster of oppositely disposed standard channel members having their ends internotched and surrounded by coupling heads in which are cast metal fillers connecting said ends and heads.

It is a further object of the invention to provide such a bolster having the ends of its tension and compression members welded together.

It is also an object of the invention to construct the compression member with a downwardly curved portion intermediate its ends and to connect such portions to the tension member by a strut column connected to said members by metal fillers cast about the same.

These and other objects and advantages of the invention will be fully set forth in the following description made in connection with the accompanying drawings in which like reference characters refer to the same parts throughout the different views, and in which

Fig. 1 is a view in side elevation of the bolster, the central portion and one end thereof being shown in section, parts of the side frame being also shown;

Fig. 2 is a central vertical section of the bolster;

Fig. 3 is a top plan view of the central portion of the bolster; and Fig. 4 is a horizontal section taken on the line 4-4 of Fig. 1.

Referring to the drawings, the bolster is shown as comprising the compression member 1 and the tension member 2, both of which members are constructed of standard channel beams having their flange portions directed inwardly or toward each other. In Fig. 1, the sand plank *a* with the spring plate riveted thereto is also shown as well as to the bolster springs *b* and the bearings and bearing plate for the bolster thereabove.

Bolster side bearings *c* are also shown as disposed on the top of the bolster.

The flanges of the tension member 2 are notched, as shown, at 1 and the flanges of the compression member 1 which member is of shorter length than the member 2, are correspondingly notched, as shown, so that the end of the flanges in the member 1 substantially abut the outer notch in the member 2 and the inner notches in the flanges are also substantially in abutting relation. The flanges of the members 1 and 2 are thus superposed and internotched, and the contacting edges of these flanges extending

from the end of the member 1 to the point 2^a, preferably are welded together. The members 1 and 2 thus form a rigid frame. Coupling heads 3 are provided at the ends of the bolster which heads are hollow and have the

ends of the members 1 and 2 disposed therein, the member 2 extending to the outer end of said head. The web portion of the member 2 is provided adjacent its ends in the head 3 with spaced holes 2^b and 2^c and the

coupling head 3 is provided in its upper side with outwardly flaring holes 3^a arranged in alinement with the holes 2^b and 2^c. The web of the member 1 adjacent its end is, likewise, arranged with holes in alinement with the holes 2^c. The head 3 is further pro-

vided with recesses 3^b in its bottom portion in alinement with the holes 2^b and 2^c of the member 2. The coupling head is secured to the ends of the tension and compression members by a cast metal filler poured into said head about the engaging ends of said members. This cast filler does not fill the entire space between the webs of the members 1 and 2, but columns of this cast metal

3^c extend from the top of the coupling head where they fill the holes 3^a, to the bottom thereof, where they merge with the filler below the web of member 2, said columns passing through the holes in the web 2. The upper and lower sides of the coupling head are thus rigidly and securely tied together and the coupling head is securely and rigidly connected to the members 1 and 2. It

will, of course, be understood that parts 1, 2 and 3 are surrounded by suitable molds and during the casting or pouring operation suitable cores are used to form columns 3^c. The coupling heads 3 are also provided with

lateral openings 3^d through which the cast filler extends, the sides of said head being formed, as shown in Fig. 4, the said heads

having somewhat enlarged openings 3^e at their inner and outer ends.

The compression member 1, as shown in Fig. 1, is formed centrally with a downwardly curved portion or depression 1^b and is connected at this portion to the central portion of the member 2 by a strut member 4. This strut member comprises a central bearing member 5, the central hub portion 10 of which rests on top of the web of member 1, the side portions of which extend downward a short distance at each side of the flanges of the member 1, a recess 5^a being formed between the web 5^b of member 5 and 15 the top side of member 1. The top plate of column 4 is curved to correspond with the curve of the member 1 and is spaced slightly from the web portion thereof, the central hub portion of member 4 being in 20 contact with said web. A plurality of outwardly flaring spaced holes 5^c are formed through the web 5^b and downwardly flaring holes 4^a aligned with the holes 5^c are also formed through the top plate of member 4, 25 a corresponding number of aligned cylindrical holes being formed through the web of member 1. The members 1, 4 and 5 are rigidly and permanently secured together by cast metal disposed in the recess 5^a in 30 the space between the web of member 1 and the top plate of member 4, which metal extends through the holes 4^a, 5^c and the holes formed in the web of member 1. The parts are thus very securely tied to the top plate 35 of member 4 by the metal extending through the aligned holes described.

As shown in Fig. 2, the member 4 is disposed inside of the channel member 2 and formed with a channel in its bottom portion, the edges of which contact with the web of the channel member 2, a space thus being formed between said web and the bottom of said groove extending between the flanges of the member 2. An aperture 2^a 40 is centrally formed through the web 2 and the parts 4 and 2 permanently secured together by a cast metal filler disposed between the same and extending into the hole 2^a. It will, of course, be understood, that 45 the members 1, 2, 4 and 5 are surrounded by suitable molds when the cast metal is poured thereinto. The members 1 and 2 are thus very rigidly and permanently connected at their central portions.

From the above description it is seen that 55 applicant has provided an exceedingly rugged and rigid construction of bolster and one having ample strength, and yet, which can be made comparatively light. The use 60 of the standard channels for the tension and compression members renders the bolster of inexpensive construction. It will be noted that the ends of the compression member 1 exert their stress against the ends of 65 the tension member 2 and the tension mem-

ber 2, likewise, exerts its stress against the ends of the compression member 1. The parts are thus efficiently arranged to withstand the stresses encountered and are so connected that there is practically no possibility of the same being deranged. 70

It will, of course, be understood that various changes may be made in the form, details and arrangement of the parts without departing from the scope of applicant's 75 invention, which, generally stated, consists in the matter shown and described and set forth in the appended claims.

What is claimed is:

1. A bolster comprising compression and 80 tension channel members having their flanges in superposed engagement at the ends thereof, a hollow coupling head in which the ends of said members are disposed, said head having spaced holes through the top thereof, and cast metal columns extending through said head from the top to the bottom thereof and through the holes in the top thereof.

2. The structure set forth in claim 1, the 85 holes in the top of the coupling head being outwardly flaring.

3. The structure set forth in claim 1, and 90 holes through the web of the tension member through which said columns extend.

4. The structure set forth in claim 3, the 95 compression member having holes through the web thereof in alignment with certain of the holes through the web of the tension member through which said columns extend.

5. A bolster having channel, compression and tension members having the flanges of their ends superposed, a hollow coupling head in which said ends are disposed having recesses in the bottom thereof, and a cast 105 metal filler in said head surrounding the ends of said channel members and extending into said recesses.

6. The structure set forth in claim 1, said 110 heads having recesses in the bottom thereof in alignment with said holes in the top thereof into which said columns extend.

7. A bolster having channel, tension and 115 compression members and a strut connecting the same at the central portions thereof and secured thereto by cast metal.

8. A bolster having a channel compression member, a central bearing plate having a portion spaced from the top thereof and having flanges extending downwardly at each side thereof forming a space between it and the top and sides of the channel, and a cast metal filler in said space securing said bearing plate to said channel member. 120

9. The structure set forth in claim 8, and 125 upwardly flaring holes through said central bearing into which said cast filler extends.

10. The structure set forth in claim 8, said 130 bolster having a tension member and a strut column extending from said compression

channel member to said tension member, the bottom side of said strut column being spaced from the said channel member, and a filler of cast metal between said member and the channel, securing the said members together.

11. The structure set forth in claim 10, said strut column having downwardly flaring holes therethrough into which said filler extends.

12. A bolster having a channel compression member with the flanges thereof directed downwardly, a central bearing member superposed on said channel and spaced therefrom, having upwardly flaring holes therethrough, a strut column having its upper side disposed between the flanges of said channel member and spaced from the web thereof and having downwardly flaring holes therethrough, and said channel having holes through the web thereof, the said holes in the central bearing, channel and strut column being in alinement, and a filler of cast metal in the space between the channel and central bearing and between the channel and strut column and extending through all of said holes.

13. A bolster having a channel tension member having upwardly directed flanges, a strut column extending across said channel member and having a recess therein spaced from the web of said channel member, and a filler of cast metal disposed in said recess and securing said strut column to the tension member.

14. The structure set forth in claim 13, said tension channel member having a hole through the web thereof into which said cast metal filler extends.

15. A bolster comprising tension and compression members, both made from superposed standard channels, the ends of the compression member being disposed in notches formed in the tension member, the sides of said notches forming acute angles, the vertices of which are directed outwardly of said members.

16. A bolster comprising tension and compression members formed of standard channels, and a hollow coupling head having the ends of said members disposed therein and secured thereto by cast metal fillers surrounding the ends of said members, the compression member terminating short of the end of the tension member.

17. A bolster having a compression member formed of a standard channel with the flanges turned downwardly, said compression member having a central downwardly curved portion in both its web and flange portions.

18. A bolster having compression and tension members having their ends in engagement, a hollow coupling head in which said ends are disposed, said head having a flaring opening at its inner end, and a cast metal filler therein surrounding the ends of said members.

19. A bolster comprising compression and tension members, a hollow coupling head in which the ends of said members are disposed, said head having openings through the sides thereof, and a cast filler in said head extending through said opening and around the ends of said members.

In testimony whereof I affix my signature. 75
EDWIN C. WASHBURN.
